UNITED STATES PATENT OFFICE.

FRANK F. LANDIS, OF WAYNESBOROUGH, PENNSYLVANIA.

STRAW-STACKER.

SPECIFICATION forming part of Letters Patent No. 537,690, dated April 16, 1895.

Application filed November 8, 1894. Serial No. 528,204. (No model.)

To all whom it may concern:

Be it known that I, **FRANK F. LANDIS**, a citizen of the United States, residing at Waynesborough, in the county of Franklin and State of Pennsylvania, have invented certain new and useful Improvements in Straw-Stackers; and I do hereby declare the following to be a full, clear, and exact description of the invention, such as will enable others skilled in the art to which it appertains to make and use the same.

This invention relates to straw stackers in which the straw is elevated by means of centrifugal force accompanied by a current of air; and it consists in the novel construction and combination of the parts hereinafter fully described and claimed.

In the drawings: Figure 1 is a side view of a pneumatic straw stacker constructed according to this invention. Fig. 2 is a side view of the discharge pipe and the means for supporting and operating it. This view is drawn upon two sheets as it could not be placed upon a single sheet and be clear. Fig. 3 is a side view of a portion of the deflector pipe showing it in a straight position. Fig. 4 is a part cross-section of the deflector pipe, taken on the line $x - x$ in Fig. 3. Fig. 5 is a detail view of a part of one of the series of springs, for operating the segments of the deflector pipe, when made in a single piece. Fig. 6 is a rear view of the standard for supporting the discharge pipe. Fig. 7 is a rear view of the top of the said standard showing a modification in the arrangement of the rope sheaves. Fig. 8 is a plan view of the mechanism for oscillating the discharge pipe. Fig. 9 is a longitudinal sectional plan of the straw chamber and the discharger casing, showing the mechanism for feeding the straw to the discharger. Fig. 10 is a view similar to Fig. 9 but shows a modification in the form of the feed mechanism. Fig. 11 is a side view showing a modification of the deflector pipe.

45 A is the end portion of the casing of a thrashing machine or separator which may be of any approved construction adapted to separate the grain from the straw and to discharge the straw at the rear end of the machine.

B is the straw chamber, at the rear end of

the thrashing machine, for receiving the straw and chaff from the separating mechanism.

B' is the discharger casing secured outside the casing A' at one end of the chamber B. 55 This discharger casing is preferably provided with a conical throat piece b.

C is the discharger shaft journaled in bearings C', secured to the casings A and B, and provided with a belt pulley c for revolving it. 60 The direction of revolution is indicated by arrows in the drawings.

D is the discharger secured upon the shaft C inside the casing B. This discharger consists essentially of a disk provided with arms. 65 The discharger is laterally movable and operates to catch the straw and forcibly project it up the delivery pipe d, as fully described in the Patent No. 512,553, issued to me on January 9, 1894. In carrying out the present 70 invention the discharger may be constructed in various forms.

The discharger is not a simple blast fan which produces a current of air, as such a fan would become choked by the straw, but it is a device specially constructed for operating positively upon the straw and flinging it up the delivery pipe. The discharger produces a blast of air as well, and the blast of air assists in keeping the straw in motion in the discharge pipe and packs it downward on the stack. 75 80

The straw is fed from the straw chamber to the discharger by means of one or more spiral blades E, which are secured to the discharger and its shaft and revolve with them. Two blades E are preferably used. In a simple form of this device (shown in Fig. 10) the pitch of each spiral blade is uniform throughout, but it may be made variable and increasing toward the end nearest to the discharger. One end of each blade is secured to the discharger, and the other end is secured to an arm e on the discharger shaft. 85 90

Spiral ribs E' are preferably secured to the 95 inside of the straw chamber to assist in propelling the straw toward the discharger, but they are not essential as the feed device will work without them.

In the form of the feed device shown in Fig. 9 each blade is bent to form a series of spirals which gradually increase in pitch, the

pitch being greatest at the end next to the discharger. The spiral ribs E', when used, are preferably arranged so as to be substantially at right angles to the parts of the spiral 5 blades adjacent to them, to avoid all shearing action which tends to break the straw. The straw which falls into the end of the straw chamber farthest from the discharger is revolved by the spiral blades and is propelled 10 toward the discharger with constantly increasing velocity, its progress being assisted by the spiral ribs and the current of air drawn in by the discharger.

When the blades are bent to form a series 15 of spirals, a series of arms is preferably provided to support them and keep them from becoming bent out of shape. When the spiral blades increase in pitch toward the discharger, the spiral ribs decrease in pitch as 20 shown in Fig. 9. The motion of the spiral blades where distant from the discharger tends chiefly to propel the straw toward the discharger and imparts but little revolving or whirling motion to it, so that there is no power 25 wasted in whirling the straw around, and the straw is not broken. The motion of the spiral blades near the discharger tends to whirl 30 around the straw rapidly and to propel it through the throat piece into the discharger casing.

In order that the blades may whirl around the straw at the entrance to the discharger casing, the ends 80 of the blades adjacent to the discharger are arranged substantially radial to, and in the same plane with, the axis 35 of the shaft C, as indicated by the dotted lines in Fig. 1.

The delivery pipe d extends vertically to the top of the machine casing A, and has a 40 flexible junction pipe d' journaled on its end and joining it to the discharge pipe F.

The flexible junction pipe d' is constructed so as to permit the discharge pipe F to be moved about freely in a vertical plane. It 45 may be made in any manner that will permit it to accomplish its purpose, but it is preferably constructed as shown and described in the Patent No. 514,266, issued to me on February 6, 1894.

50 In carrying out the present invention the discharge pipe need not be made extensible, but when an extensible discharge pipe is required the same is preferably made of two sections of which the upper section F' slides telescopic over the lower section F.

G is a circular bracket secured to the top of the machine casing A concentric with the delivery pipe d, and G' is a removable ring secured to the top of the said bracket.

60 H is the cylindrical base of the standard H' for supporting the discharge pipe. This base is provided with a flange h, and two series of balls g are provided and arranged between the said flange and the bracket G and ring G'.

65 The flange h comes between the two series of balls, and the balls are arranged to turn freely

so that the base H may be revolved in either direction in the bracket G with the least possible friction. In carrying out this invention however, the base H may be journaled in the 70 support in any other manner that will permit it to turn freely.

The sides of the standard H' consist of two bars I which preferably have their lower ends pivoted to the lugs h' of the base H by means 75 of the pins i, so that the standard can be folded over in shipping the thrashing machine. I' are the stays which support the bars I. These stays preferably consist of one or more chains attached to the upper part of 80 the bars I and to a lug i' on the rear part of the base H.

J is a ring secured to the discharge pipe F and provided with rearwardly-extending arms j, which are pivoted to the said lugs h' by the 85 said pins i, so that the angle of the discharge pipe may be varied.

The angle of the discharge pipe is changed and varied by means of the winch J' which is secured to the standard H', and a cord j' connected to the said winch and to the upper part 90 of the discharge pipe.

When the discharge pipe is extensible, the upper pipe section F' slides through a ring K, and k are longitudinally-arranged bars secured to the rings K and J. The said rings are preferably provided with lugs k' for the attachment of the bars k, which may conveniently be formed of wood, or metal tubes may be used if preferred. Four bars k arranged 95 equidistant from each other are found to work well, but the number of the bars may be increased or diminished if desired.

The ring K has a bracket 2 on its upper side, and 3 and 4 are two sheaves journaled on the 100 pin 5 in the said bracket.

A bracket 6 is secured to the upper side of the lower end of the pipe section F', and 7 is a sheave journaled in the said bracket on the pin 8.

110 A bracket 9 is secured to the upper end of the pipe section F', and 10 is a sheave journaled in the bracket 9 on the pin 11.

Two sheaves 12 and 13 are journaled on a pin 14 at the top of the standard H' and preferably between the two bars I.

The cord j', or its equivalent, such as a wire rope or chain, is secured at one end to the lug 15 on the ring K. Thence it passes around the sheave 10 and downward over the sheave 12, from the underside of the sheave 12 to the upper side of the sheave 3, from the underside of the sheave 3 around the sheave 7 to the underside of the sheave 4, from the upper side of the sheave 4 over the sheave 13, 125 and thence downward to the winch J, or other equivalent mechanism for winding up the cord, secured to the standard.

The telescopic sections of the discharge pipe remain in whatever position they are 130 placed, the upper pipe section being sustained by the friction of the various movable parts.

When the winch is revolved to wind up or to let out the cord, the angle of the pipe is changed, but the length of the pipe remains constant, as the cord merely turns all the 5 sheaves except the sheave 10 and does not slide the pipe section F' either in or out.

The pipe section F' is slid in or out by pulling upon any one of the intermediate portions of the cord j'. When this is done, all the 10 sheaves are turned except the sheave 13. The angle of the pipe is not appreciably changed, and the winch remains stationary.

The pipe section F' may be operated in other ways. For instance, the sheave 12 may 15 be journaled on the pin 14 outside the bars I, as shown in Fig. 7. This sheave then has a crank handle 12' secured to it, and the pipe section F' is operated by revolving the crank handle 12'.

20 M is the deflector pipe attached to the upper end of the discharge pipe. When the discharge pipe is not extensible any approved form of deflector or deflector pipe may be used. When the discharge pipe is extensible, 25 the deflector pipe M is preferred because of the inconvenience in making the discharge pipe revolvable as well as extensible. The deflector pipe M may also advantageously be used upon discharge pipes which are not extensible.

30 The deflector pipe M consists of a series of overlapping conical segments m, the lower end segment being secured to the discharge pipe. The segments m are operatively connected 35 together by means of three or more straps m' of flexible material. Four leather straps arranged equidistant from each other are preferred. Each strap is secured to all the segments by bolts or rivets at points where the 40 segments never overlap, and the straps are made of a length sufficient to permit the segments to be bent over to the greatest requisite curvature.

Eyes N are secured to the segments at intervals 45 between the straps, and cords n are secured to the upper end segment and are passed through the said eyes. Four cords are preferably used and are arranged at the top and bottom and on each side of the pipe. The 50 eyes N are preferably attached to each alternate segment, and the deflector pipe is moved sidewise or up or down by pulling and loosening the cords in an appropriate manner.

O are springs which operate to hold the deflector pipe in a straight position and in line 55 with the discharge pipe when the cords n are slack. These springs preferably consist of a central loop, and arms having eyes at their ends encircling the shanks of the eyes N, as 60 shown in Figs. 3 and 4, but if desired the springs may be made continuous as shown in Fig. 5 which also shows the shape of the spring arms and loops before being attached to the pipe. When attached to the pipe, the 65 springs are under a tension sufficient to hold the segments thereof in a straight position.

If desired, the springs can be attached to each segment instead of to each alternate segment. The springs then form the flexible connection between the segments, and the 70 straps m' can be dispensed with, as shown in Fig. 11.

When the discharge pipe is extensible, the cords n are preferably passed over sheaves 20 journaled on pins 21 projecting from lugs on 75 the ring J, and are thence led through eyes 22 at the lower end of the pipe segment F', over the sheaves 23 journaled on pins 24 and carried by the ring K, and have their ends secured to the pins 25 near the eyes 22. This 80 arrangement holds the cords n extended and in a convenient position to be operated, and the action of sliding the pipe section F' has no effect on the length of the said cords.

Each cord n is provided with a retaining 85 device for holding it when it has been pulled upon to bend the deflector pipe. A simple form of retaining device which may advantageously be used consists of a lever 28 pivotally supported by the ring J, and provided 90 with a pivoted shoe 29. The pivot of the shoe is arranged a little to one side of a line drawn between the centers of the pivots of the lever and of the sheave, so that when the shoe is pressed against the cord by means of 95 the lever, the friction between the shoe and the cord assists in pressing the shoe against the cord and prevents the cord from slipping.

In carrying out this invention, the discharge pipe is made longer than shown in the drawings, and if desired it may be made with more than one sliding section. The deflector pipe can be raised to the position shown in dotted lines in Fig. 2 by pulling the top cord n. This is advantageous, as in topping off a 105 straw stack it is sometimes desirable to throw the straw upward.

In building a straw stack, the discharge pipe and its supporting standard may be oscillated by the automatic mechanism shown 110 in Fig. 8.

P is a belt pulley which is revolved constantly from any convenient shaft of the thrashing machine. The belt pulley P is secured on a shaft p which is journaled in a 115 bracket P' secured to the frame A of the machine. A beveled toothed wheel 30 is secured on the shaft p, and gears into the two beveled toothed wheels 31 and 32 which are mounted on the shaft 33. The shaft 33 is journaled in 120 the bracket P' and has a double clutch jaw q splined to it. The wheels 31 and 32 have clutch jaws q' and are revolved constantly in opposite directions. Driving mechanism is provided which connects the standard with 125 the said shaft 33 so that the standard is oscillated by sliding the double clutch jaw q into engagement with the single clutch jaws alternately.

A convenient form of driving mechanism 130 consists of a worm 36 secured upon the end of the shaft 33 and gearing into a worm wheel

37 journaled on a vertical pin 38 projecting from the bracket P'. A chain wheel 39 is secured to the worm wheel 37, by a pin 39' which is easily removed, and 40 is a drive chain which engages with the said chain wheel and with sprockets 41 projecting from the cylindrical base H.

The direction and amplitude of the oscillations are controlled by removable pins 42 inserted into holes 43 in the base H.

R is a bell-crank lever pivoted on the pin 44 projecting from the flange of the base H. One arm of this lever is arranged in the path of the pins 42, and the other arm is provided 15 with a blunt wedge-shaped head 45.

S is a lever pivoted on a pin s projecting from the bracket P'. One end of this lever operates the double clutch jaw, and t is a rod pivoted to the other end of the lever S. A 20 blunt wedge-shaped projection t' is formed on the side of the rod t and is arranged opposite the head 45 with the points of the wedges toward each other.

T are pins for limiting the movement of 25 the bell-crank lever R, and 46 is a guide for the free end of the rod t. A spring 48 is provided for pressing the projection t' against the head 45.

When one of the pins 42 strikes the bell-30 crank lever R, the head 45 pushes back the projection t' against the tension of the spring 48, and the apex of the head is moved to the other side of the apex of the projection. The spring 48 then presses the meeting flanks of 35 the head and projection together, and this pressure causes the rod t to move longitudinally and to slide the double clutch jaw out of engagement with one single clutch jaw and into engagement with the other. The discharge pipe and its standard are oscillated 40 continuously and the amplitude of the oscillations is regulated by placing the pins 42 in different holes of the base H.

It will be noticed that the sections of the 45 discharge pipe are supported by the lifting cord near their upper ends whether the upper section is extended or not, so that there is no tendency for the upper section to stick in sliding.

50 What I claim is—

1. In a straw stacker, the combination, with a centrifugal discharger, of a feeding device comprising a spiral blade extending longitudinally of the straw chamber and secured 55 to the discharger shaft, that portion of the blade next to the discharger being substantially radial to and in the same plane with the axis of the said shaft, whereby the straw is revolved in the said chamber and propelled 60 toward the discharger.

2. In a straw stacker, the combination, with a centrifugal discharger, of a feeding device comprising a spiral blade increasing in pitch as it approaches the discharger, the said 65 blade being secured to the discharger shaft, extending longitudinally of the straw cham-

ber, and that portion of the blade next to the discharger being substantially radial to and in the same plane with the axis of the said shaft, substantially as set forth. 70

3. In a straw stacker, the combination, with a centrifugal discharger, and its driving shaft; of a feeding device consisting of two spiral blades each supported at one end by the discharger, and an arm secured on the said shaft 75 and supporting the other ends of the said blades, those portions of the blades next to the discharger being substantially radial to and in the same plane with the axis of the said shaft. 80

4. In a straw stacker, the combination, with a centrifugal discharger, and its driving shaft; of a straw chamber arranged substantially concentric with the said shaft and provided with spiral ribs; and spiral blades secured to 85 the said shaft and increasing in pitch as they approach the discharger, those portions of the blades next to the discharger being substantially radial to and in the same plane with the axis of its shaft, and the said ribs being 90 arranged substantially at right angles to the parts of the said blades adjacent to them, substantially as set forth.

5. In a straw stacker, the combination, with the delivery pipe, the flexible junction pipe, 95 and the discharge pipe; of the rearwardly extending arms secured to the discharge pipe; a supporting standard having the said arms pivoted to it, and provided with a revolvable base portion encircling the said delivery pipe 100 and having a projecting circular flange; a stationary circular support arranged concentric with the said base and its flange; and two series of anti-friction balls arranged above and below the said flange between the 105 base and its stationary support, substantially as set forth.

6. In a straw stacker, the combination, with a supporting standard, of a discharge pipe formed of telescopic sections, the lower section being attached to the said standard, cord 110 sheaves carried by the said pipe sections and standard, and a cord passed around the said sheaves and operating to slide the upper pipe section when pulled upon without altering the 115 length of the cord, substantially as set forth.

7. In a straw stacker, the combination, with a supporting standard, of a discharge pipe formed of telescopic sections, the lower section being hinged to the said standard, cord 120 sheaves carried by the pipe sections and standard, a cord passed around the said sheaves and operating to slide the upper pipe section when pulled upon without altering the length of the cord, and winding mechanism for changing the length of the said cord and thereby varying the angle of the discharge pipe, substantially as set forth. 125

8. In a straw stacker, the combination, with a supporting standard, of the two rings J and 130 K connected together, the lower ring J being attached to the standard; the lower pipe sec-

tion F secured to the ring J, the upper pipe section F' sliding through the ring K and over the pipe section F, and the cord sheaves and cord connected to the pipe sections and stand- 5 ard, substantially as set forth.

9. The combination, with a discharge pipe; of a deflector pipe secured to the end thereof and formed of conical segments, and springs connecting the said segments together, nor- 10 mally holding the deflector pipe straight and in line with the discharge pipe, and permit- 15 ting it to be bent in any direction, substan- tially as set forth.

10. The combination, with a discharge pipe; 15 of a deflector pipe secured to the end thereof and formed of conical segments, and springs connecting the said segments together and normally holding the deflector pipe in line 20 with the discharge pipe; eyes secured to the said segments and supporting the said springs; and cords secured to the end segments, passing through the said eyes, and affording means for bending the deflector pipe in any direction substantially as set forth.

25 11. The combination, with a discharge pipe, of a deflector pipe secured to the end thereof and formed of articulated conical segments operatively connected together, and springs normally holding the deflector pipe straight 30 and in line with the discharge pipe, and per- mitting it to be bent in any direction.

12. The combination, with a discharge pipe 35 formed in telescopic sections, of the rings J and K and the bars connecting them, the lower ring J being secured to the lower pipe section; a deflector pipe formed of articulated conical segments operatively connected together and to the end of the upper pipe sec- 40 tion; cord sheaves carried by the rings J and K, cord guiding eyes, and the operating cords

attached to the free end of the deflector pipe, passing through the said eyes and over the said sheaves and attached to the lower end of the upper pipe section, substantially as set forth. 45

13. The combination, with a discharge pipe, of a deflector pipe formed of articulated conical segments operatively connected together and to the upper end of the discharge pipe, and springs normally holding the said seg- 50 ments extended and substantially in line with the discharge pipe; cord guiding eyes project- 55 ing from the deflector pipe, cords secured to the free end of the deflector pipe and passing through the said eyes, and clamping de- vices for securing the said cords to the lower part of the discharge pipe after the deflector pipe has been adjusted.

14. The combination, with a revolvable standard, and a straw stacker discharge pipe 60 supported thereby; of driving mechanism for turning the said standard and pipe, clutch mechanism for changing the direction of motion, a pivoted lever for operating the clutch mechanism, the rod pivoted to the said lever 65 and provided with the projection t', a pivoted bell-crank lever provided with the head 45, stop pins for limiting the movements of the bell-crank lever, tappet pins projecting from the said standard and adapted to turn the 70 bell-crank lever on its pivot, and a spring pressing the projection t' against the head 45, whereby the said pipe is caused to oscillate, substantially as set forth.

In testimony whereof I affix my signature 75 in presence of two witnesses.

FRANK F. LANDIS.
